UNITED STATES PATENT OFFICE

CARLIN A. WALSH, OF CAMBRIDGE, MASSACHUSETTS

FOOTWEAR

Application filed October 29, 1930. Serial No. 491,966.

My present invention relates to footwear, and more particularly to a combined leg and stocking and shoe protector.

An important object of the present invention is the provision of a protector of this nature which is preferably constructed either of elastic material, or is provided with means to sustain the protector in adjusted position. Preferably the protector will be constructed 10 of thin rubber.

Another object of the invention resides in the provision of a protector from which seams, closure fasteners, and other undesirable elements are absent, my novel protector 15 constituting a unitary, seamless device.

Another and important object of the invention resides in the provision of means to enable the individual wearer to instantly adjust the height of the protector on the leg to 20 any desired position.

Another object of the invention resides in so constructing the bottom or sole portion of my novel device that it may be easily flexed for removal, folding, or the like.

Other objects and features of the invention, 25 reside in the particular construction and arrangement of my novel footwear, and the above and other objects and features of the invention, as well as details of construction, 30 will be hereinafter more fully pointed out, described and claimed.

Referring to the drawings, illustrating a preferred embodiment of the present invention,

Fig. 1 is a side elevation of my novel protector in wearing position;

Fig. 2 is a front elevation of said protector;

Fig. 3 is a fragmentary rear elevation 40 thereof;

Fig. 4 is a bottom plan view;

Fig. 5 is a fragmentary cross sectional view on the line 5—5 of Fig. 1;

Fig. 6 is a longitudinal sectional view;

Fig. 7 is a cross sectional view on the line 7—7 of Fig. 6;

Fig. 8 is a longitudinal sectional view illustrating a modification; and

Fig. 9 is a fragmentary top plan view illustrating a slight further modification.

Referring now to the drawings for a particular description of the invention, 1 designates a continuous foot and leg piece, which is preferably formed as a seamless unitary member, of elastic material, preferably a high grade rubber which may be, and preferably is, quite thin. Around the open end of the device I provide a beading 2, secured thereto in any desirable manner, as by vulcanizing, the exposed surface of said beading, 55 or a portion or portions thereof, being knurled or roughened, as clearly illustrated in Figs. 1 and 2. The beading 2 is likewise of rubber, and is of a size to insure gripping thereof around the leg at substantially any position to which said beading is adjusted. 60 Because of the presence of the rubber beading 2, I may, if desired, construct the foot and leg portion 1 of other flexible material, such as rubberized silk, in which event the beading 2 will constitute sustaining means 65 for the protector.

When manufacturing the device, a desirable method of forming the foot and leg portion 1 as a unitary seamless member is to utilize a last or form, and subject the same to a dipping operation or operations, subsequently affixing the rib 2 to the formed foot and leg member. However, I do not limit myself to any particular method of manufacturing this device. 75

Subsequent to the formation of the foot and leg member 1, a sole 3, preferably corrugated, is then applied to the tread portion of the member 1, this sole 3 terminating at the 85 forward end of the shank portion. A heel 4, also preferably corrugated, is applied, and in the case of a high heeled protector, a breast portion 5, preferably integral with the heel 4, is also utilized. If desired, the entire 90 heel portion of the protector may be enclosed in a protecting cupped heel. At each side of the member 1 I apply a reenforcing strip or layer 6, extending from the outer edge of the shank portion upwardly to the 95 ankle portion, these 2 layers 6 preferably increasing in width toward the ankle portion, and meeting or substantially meeting in the front and back, as clearly illustrated in Figs. 2 and 3. There is thus left a considerable por-

tion of the protector itself along the shank portion, as at 7, which permits easy flexing of the protector at this point for removal of the same from the foot of the wearer, and this point of flexure will also permit easy folding of the supporter for insertion in a handbag or other container.

Many attractive color combinations are possible in my novel protector. For example,

10 the foot and leg portion 1 may be of one color, and the reinforcing layers or strips 6 of another color, and, if desired, the beading 2 may be of a still further color.

Thus, it will be appreciated that I have devised an attractive, protective, waterproof and efficient shoe and stocking protector, as well as a foot and leg protector, which is also capable of having incorporated therein many desirable contrasting color combinations to appeal to the aesthetic taste of the wearers.

Should the wearer not desire the protector to be extended to its limit, as illustrated in Fig. 1, the wearer, by simply rolling the protector downwardly from the top, will roll the leg portion 1 around the beading 2, the knurled surface or portions of said beading 2 assisting in this rolling and furthermore insuring against looseness or undue gathering of the leg portion 1 at the rolled point. Thus, the protector may be rolled to the position illustrated in dotted lines at 8 in Fig. 1 to merely cover the foot and calf, or I may roll the protector still further to the point 35 illustrated in dotted lines at 9, in Fig. 1, to simply cover the foot and ankle. If desired, the protector may be so constructed that when in fully extended position it will only reach to the point 8 in Fig. 1, or may be made of any determined length desired.

In Fig. 8 I have illustrated a slight modification, wherein the foot portion of the protector is provided with an extra layer 10, completely surrounding and enclosing the 45 foot portion of the protector. If thin material is utilized for the protector, this additional layer may be found desirable to eliminate undue wear by the shoe or parts thereof. After the attachment or formation of the enclosing layer 10, the sole and heel, 3 and 4 respectively, will then be attached and the protector finished in the usual manner. When the additional enclosing layer 10 is utilized, still further contrasting color combinations are possible, since the layer 10 may be of a color to contrast with the color of the leg portion 1, as will be readily understood.

In Fig. 9 I have illustrated the addition of a toe strip 11, this toe strip extending upwardly over the instep to constitute a reinforcing layer over the closure portion of the shoe, and to increase the strength and wearing qualities of the protector at this point.

My novel protector possesses the further advantage of being form fitting to a de-

gree not possible in a protector utilizing any type of closure fasteners. It is attractive and neat and because of the presence of the beading 2 and the facility with which the protector may be rolled, easily put on and taken off. My novel protector is light in weight, and protects the shoes and hosiery of the wearer from rain, mud, spots, or other injurious factors.

I may also provide a beading 12, surrounding the leg portion closely adjacent to the top of the foot portion, as clearly illustrated. This beading 12 serves a dual function. When rolling the leg portion downwardly over the beading 2, as illustrated in successive stages at 8 and 9, the rolled leg portion may be rolled over the beading 12, which will hold the said rolled portion in adjusted position. Also, should the foot portion of the protector become injured or destroyed, 85 said foot portion may be severed from the remainder of the protector, below the beading 12, in which case a unitary legging defined at its upper and lower extremities by the beading 2 and beading 12, will be provided. 90 The beading 12 is of elastic material, preferably rubber, so that it will not interfere with the removal of the protector over the foot and shoe of the wearer.

I believe that the protector illustrated and described in this application is novel, and I have therefore claimed the same broadly in the present application.

While I have necessarily described my present invention somewhat in detail, it will be appreciated that I may vary the size, shape, and arrangement of parts within reasonably wide limits, without departing from the spirit of the invention.

My invention is further described and defined in the form of claims as follows:

1. A protector of the kind described, comprising an integral seamless foot and leg enclosing portion, a sustaining beading of elastic material affixed to the open end of 110 said protector, and reinforcing strips affixed to the foot portion of said protector and extending upwardly on each side thereof, from the shank portion to the ankle portion.

2. A protector of the kind described, comprising an integral seamless foot and leg enclosing portion of waterproof material, a sustaining beading of elastic material affixed to the open end of said protector, a reinforcing strip affixed to each side of the foot portion of said protector and extending upwardly from the shank portion to the ankle portion, a sole, and a heel, said sole terminating adjacent to the forward end of the shank portion, whereby a flexible area is provided 120 between the sole and the heel for collapsing or folding of the foot portion of the protector.

In testimony whereof, I have signed my name to this specification.

CARLIN A. WALSH.
